UNITED STATES PATENT OFFICE.

EDWARD J. SCHROEDER, OF JERSEY CITY, NEW JERSEY.

SHADE-HOLDER.

1,158,731.

Specification of Letters Patent.

Patented Nov. 2, 1915.

Application filed November 13, 1914. Serial No. 871,869.

To all whom it may concern:

Be it known that I, EDWARD J. SCHROEDER, a citizen of the United States, residing at Jersey City, in the county of Hudson and State of New Jersey, have invented certain new and useful Improvements in Shade-Holders, of which the following is a specification.

This invention relates to shade holders for electric lamps and more particularly to those provided with key sockets, and its novelty consists in the construction and adaptation of the parts as will be more fully hereinafter pointed out.

The object of the invention is to provide a simple cheap construction, one not liable readily to be displaced, strong enough for the purpose and readily assembled and disassembled.

In the drawings, Figure 1 is a front elevation of a device embodying the invention, some of the parts being cut away to show concealed parts. Fig. 2 is a central vertical section through the same, but showing a reinforcing shell, while Figs. 3, 4 and 5 are sections showing different arranged constructions and positions of the shells of the holder.

In the drawings, 10 is a socket support of any suitable form. It may be a depending pipe, a hickey, or any of the fittings common to the art. Of whatever form, however, it should be provided with a downwardly extending neck 11 to connect with the upwardly extending nipple 12 of a socket 13 adapted to support the electric lamp (not shown) in the usual manner. This socket may be provided with a key indicated at 14 or it may be of the keyless type.

The shade holder is adapted to surround the socket and to depend either from it or from the socket support. It comprises two shells, viz., an upper shell 15 which may aptly be called a cap, and a lower shell 16 which may aptly be called a petticoat. The upper shell is centrally apertured so that it can pass over and surround the neck 11 of the fitting, and it is provided with a downwardly extending threaded annular flange 17. The lower shell is petticoat or bell shaped, is provided with an upper threaded section 18 to engage the annular flange 17, and is also provided with a suitable recess 55 to receive the socket key, with stiffening corrugations or ribs indicated at 19, and slits

indicated at 20. It is also provided with means for securing and supporting a shade 21 consisting of an outward expansion at 22, an inward contraction at 23, and an outward expansion at 24, in connection with a clamping ring indicated at 25. This form of holder is readily assembled and is shown in its simplest form in Fig. 1, in which the holder closely hugs the socket and is in effect supported thereby. It will be understood however that the particular form of holder so far as its connection with the shade is concerned forms no part of this invention. Any appropriate design of shade holding device may be employed.

In the form shown in Fig. 2, where there is an appreciable distance between the socket and the holder, the upper or cap portion of the latter may be made so light that it might collapse under unusual conditions of installation or operation. To prevent this, there is provided a reinforcing member 26 for the holder. It comprises a shell of much the same general shape as the cap 15 and with a depending flange 28 which extends downwardly far enough adequately to support this cap. The advantage of all of these constructions is that the upper shell or cap is rotatable with respect to the lower shell or 85 petticoat and that the former and the reinforcing member are rotatable with respect to the socket.

In Fig. 3 there is shown a modification of the device in which the upper cap or shell 15 is fitted into an annular groove or recess above the nipple of the socket, and the lower petticoat or shell 16 is threaded into the depending flange of the upper cap as above, but the reinforcing member 26 in this case 95 is placed outside of both the upper member 15 and lower member 16 of the shell. This construction has the advantage of covering up the threads at the junction of the two shells of the holder. It is understood that 100 in such construction the upper shell 15 and reinforcing member 26 would be clamped tightly together so that they would rotate simultaneously.

In Fig. 4 there is illustrated another 105 modification of the device in order to avoid the necessity for running the reinforcing shell up to the top of the nipple. In this construction, the upper member 15 is shown as provided with an outwardly extending 110 reverted flange 29 and the lower member 16 is threaded into the lower threaded part of

such upper member. The reinforcing member 26 is provided with an annular flange 30, engaging the flange 29 and held in position thereby.

5 In Fig. 5 a construction is shown somewhat resembling that of Fig. 4. In this case, the reinforcing member 26 is provided with the outwardly extending reverted annular flange 31, and the upper member or shell 15 is provided with an annular flange 32 fitted into the flange 31.

None of these modifications, however, show any departure from the principles upon which the invention is based.

15 I claim:

1. The combination with a socket support and socket of a shade holder, comprising a cap which is rotatable with respect to a petticoat shell adapted to surround the socket and also with respect to the socket, the petticoat being adapted to carry a shade, means for securing the petticoat to the cap, and a reinforcing member rigidly secured to the cap intermediate its edges by interengaging

portions on said cap and said member, said reinforcing member extending in close proximity to the said cap and petticoat to strengthen the same.

2. The combination with a socket support and socket of a shade holder, comprising a cap provided with a flange, said cap being rotatable with respect to a petticoat shell adapted to surround the socket and also with respect to the socket, the petticoat being adapted to carry a shade, means for securing the petticoat to the cap, and a reinforcing member provided with an annular flange adapted to be secured into the flange upon the cap thereby rigidly securing the said member with respect to the cap into close proximity thereto and the petticoat to strengthen the same.

In testimony whereof I affix my signature in presence of two witnesses.

EDWARD J. SCHROEDER.
